UNITED STATES PATENT OFFICE.

EDGAR J. REILLY, OF YOUNGSTOWN, OHIO, ASSIGNOR TO THE WILLIAM B. POLLOCK COMPANY, OF YOUNGSTOWN, OHIO, A CORPORATION OF OHIO.

POURING APPARATUS FOR HOT METAL.

1,246,783.

Specification of Letters Patent.

Patented Nov. 13, 1917.

Application filed March 12, 1917. Serial No. 154,221.

To all whom it may concern:

Be it known that I, EDGAR J. REILLY, a citizen of the United States, residing at Youngstown, Mahoning county, Ohio, have 5 invented a new and useful Pouring Apparatus for Hot Metal, of which the following is a full, clear, and exact description, reference being had to the accompanying drawings, forming part of this specification, in 10 which—

Figure 1 is a side elevation of one form of apparatus embodying my invention.

Fig. 2 is a detail view, partly in section, and partly in side elevation, of a portion of 15 the apparatus shown in Fig. 1, with the ladle in a partially tilted position.

Fig. 3 is a plan view of the apparatus shown in Fig. 1, and

Fig. 4 is a detail sectional view, on the 20 irregular line IV—IV of Fig. 3.

My invention has relation to apparatus for pouring hot metal, and more particularly to pouring stands in which a ladle or other vessel is held while being emptied, 25 such as are used for transferring hot metal in and around iron and steel mills and furnaces. These ladles are of various sizes and capacities, being usually carried by overhead traveling cranes, or upon ladle cars. Some- 30 times, however, they simply receive the metal from a furnace and transfer it into molds or other receptacles, without being themselves transported to any other point.

As heretofore constructed, the bearings 35 upon the ladle which are used in the pouring operation have been subject to excessive wear, due to sliding of the bearings upon those parts of the pouring stands with which they contact. This wear is greatly aug- 40 mented by grit and other dirt which accumulates upon these surfaces, and also by the impossibility of successful lubrication. Such wear is particularly objectionable on account of the difficulty and expense of replacing the 45 bearings, and also on account of the time lost while the ladle is withdrawn from service for making the necessary repairs.

My invention provides a pouring stand in 50 which all sliding movement of the ladle bearing surfaces is eliminated, thereby eliminating the wear due to this cause. It also

provides a construction in which the wearing surfaces are protected from dirt and grit.

A further object of the invention is to 55 provide contacting and wearing parts which are of simple and inexpensive character, and which may be easily and quickly replaced between successive operations.

A still further object of my invention is 60 to provide apparatus of this character by means of which a low pour may be obtained, with a minimum splashing of the metal as it is discharged from the ladle.

My invention will be best understood by 65 reference to the accompanying drawings, in which I have shown a preferred embodiment thereof, and which will now be described, it being premised, however, that various changes can be made in the details of 70 construction and arrangement of the parts without departing from the spirit and scope of my invention as defined in the appended claims.

In these drawings the numeral 2 designates 75 a ladle having the trunnion wings 3 provided with laterally projecting trunnions 4 upon which the ladle may be supported in the usual manner on a ladle car, or which may be engaged by the hooks of a lifting 80 crane.

5 designates a stand in which the ladle may be placed for pouring. It may either receive the hot metal from the furnace while 85 on this stand, or the ladle may be transferred to this stand from a ladle car, or may be moved thereto from the furnace by means of a crane. This stand may, in general, be of any suitable character and construction, and may be either fixed as shown, or it may 90 itself be carried on a car in a manner similar to that shown in the patent to W. W. McKelvey No. 1,021,543, of March 26, 1912.

Each of the trunnion wings 3 of the ladle is provided with another set of trunnions 95 6 at a lower level than the trunnions 4, and at a point considerably to one side of the vertical center of the ladle. These trunnions preferably rest in open bearings 7 of the stand 5. Each trunnion wing is also formed 100 with an upward extension 8 having the open laterally and downwardly facing bearing re-

cess 9 therein. 10 designates the usual pouring spout or nozzle of the ladle, and 12 indicates any suitable trough or runner into which the contents of the ladle are to be 5 discharged, and by which the hot metal is conveyed to the molds.

- 13 designate two fixed stands or supports placed on opposite sides of the trough or runner 12. Each of these stands or supports 10 13 is provided at its upper portion with a movable bearing member, or cradle, 15 which is rigidly fixed to a pin or shaft 16 by a suitable fastening, such as the bolt 17. The ends of the pin or shaft 16 are 15 provided with removable bush bearings 18 in the side legs of the stand, these bearings being removably secured in place by suitable means such as the set screws 19. Each movable bearing member or cradle 15 is 20 formed with the intermediate portion 20 which forms a convexed bearing surface adapted to the concave bearing surface of the recess 9, before described. Each of said members also preferably has the upwardly 25 extending lip 21 adapted for contact with the hook portion 22 adjacent to the recess 9; and a downwardly extending lip or flange 23 adapted for contact with the trunnion wing at 24.
- 30 I also preferably provide each of the stands or supports 13 with an antifriction guard roller 25 which is mounted on a pin or shaft 26 supported in the lugs 27 of the stand or support. These rollers act as safeguards in that, if the ladle should happen to slip out of the bearing members or cradles, they will catch it.

The operation will be readily understood. In making a pour, the ladle is first tipped 40 on the trunnions 6 to bring the bearing surfaces of the recesses 9 into contact with the bearing surfaces 20 of the bearing members or cradles of the stands or supports 13, as shown in Fig. 2. The ladle may be tipped 45 in any suitable manner, as by engaging a crane hook with the lug 28 thereof. Further tipping movement of the ladle occurs on these bearings, and instead of there being any sliding movement at these bearing surfaces, the pins 16 will turn in their bush 50 bearings 18. These bearings are protected from dirt and grit, and wear therein is reduced to a minimum. If it becomes necessary to remove and replace them, this can be 55 readily and quickly done with very little loss of time.

It will be further noted that my invention provides all the advantages of a low-pour ladle which are present in structures such 60 as that of the McKelvey patent above referred to.

I claim:

1. A pouring stand for ladles, having a 65 tiltable bearing member mounted thereon for engagement with the lip portion of a

ladle when the latter is tilted into engagement therewith, substantially as described.

2. In metal pouring apparatus, a pouring stand provided with a rotatable bearing member, and with a guard adjacent to said 70 member, substantially as described.

3. In apparatus of the character described, the combination with a ladle having bearing surfaces at opposite sides of its upper portion, of fixed stands or supports adjacent to 75 the ladle when in pouring position and having rotatable bearing members or cradles adapted for engagement with the bearing surfaces of the ladle when the latter is tipped into engagement with said members, sub- 80 stantially as described.

4. In apparatus of the character described, a pouring stand comprising a fixed support, a shaft or pin having bearings in said support, and a bearing member secured to said 85 shaft or pin and adapted for engagement with the bearing surface of the ladle, substantially as described.

5. In apparatus of the character described, a pouring stand comprising a fixed support, 90 a shaft or pin having bearings in said support, and a bearing member secured to said shaft or pin and adapted for engagement with the bearing surface of the ladle, said support having removable and renewable 95 bearings for said shaft or pin, substantially as described.

6. In apparatus of the character described, a pouring stand comprising a fixed support, 100 a pin or shaft journaled in said support, and a bearing member or cradle secured to the shaft or pin and having a convex bearing portion and oppositely extended flanges or projections, said bearing portion and flanges or projections being adapted for engagement 105 with corresponding bearing portions of the ladle, substantially as described.

7. In apparatus of the character described, the combination with a tiltable vessel having open bearing recesses at opposite sides of its 110 upper portion, of fixed stands or supports adjacent thereto, and provided with rotatable bearing members or cradles adapted for bearing engagement with said recesses, substantially as described.

8. In apparatus of the character described, the combination with a stand, a ladle tiltably mounted on said stand and provided with lateral bearing recesses at its upper portion at opposite sides of its pouring spout or 120 nozzle, and fixed supports adjacent to said stand and having rotatable bearing members or cradles adapted to be engaged by said recesses when the vessel is tilted, substantially as described.

9. The combination with a tiltable ladle, of a fixed stand upon which the ladle is adapted to be tilted, said stand having a tiltable bearing to receive the ladle as it is tilted, substantially as described.

10. The combination with a tilttable ladle, of a fixed stand upon which the ladle is adapted to be tilted, said stand having a tilttable renewable bearing to receive the ladle as it is tilted, substantially as described.

11. The combination with a tilttable ladle, of a fixed stand upon which the ladle is adapted to be tilted, said stand having a tilttable bearing to receive the ladle as it is

tilted, the stand also having a ladle guard, 10 substantially as described.

In testimony whereof, I have hereunto set my hand.

EDGAR J. REILLY.
